(57) **CLAIM**

The ornamental design for a display fixture, as shown and described.

DESCRIPTION

FIG. 1 is a top and front perspective view of a display fixture, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof; and,

FIG. 8 is a top and front perspective view of a display fixture, showing one embodiment of our new design.

In the drawings, the broken lines depict unclaimed subject matter only. The heavy weight broken lines define the bounds of the claimed design and form no part thereof.
